CLAIM

The ornamental design for a beverage bottle, as shown and described.

DESCRIPTION

FIG. 1 is a front perspective view of a beverage bottle showing my new design.

FIG. 2 is a front view thereof.

FIG. 3 is a rear view thereof.

FIG. 4 is a left end view thereof.

FIG. 5 is a right end view thereof.

FIG. 6 is a top view thereof; and,

FIG. 7 is a bottom view thereof.

The broken lines in FIG. 7 depict a portion of the beverage bottle that forms no part of the claimed design.
